UNITED STATES PATENT OFFICE.

WILLIAM HOUSER, OF OBERLIN, KANSAS.

CLOSING AND LOCKING MECHANISM FOR FENCE GATES.

Application filed July 27, 1923. Serial No. 654,116.

To all whom it may concern:

Be it known that I, WILLIAM HOUSER, citizen of the United States, residing at Oberlin, in the county of Decatur and State 5 of Kansas, have invented certain new and useful Improvements in Closing and Locking Mechanism for Fence Gates, of which the following is a specification.

In carrying out the present invention it 10 is my purpose to provide a highly novel and effective closing and locking mechanism for the gates of fences, the primary object thereof being to provide such a closing and locking mechanism which is extremely simple of 15 construction and which will operate efficiently under all conditions.

An additional object of this invention is the provision of a closing mechanism for gates whereby the same may be opened either 20 inwardly or outwardly of the fence, the said means serving to normally return the gate to its closed position even though the same be upon the inner or outer side of the fence.

An additional object is the provision of 25 such a locking mechanism for fence gates wherein the same will automatically lock the gate in a closed position no matter from which direction the gate is swinging.

With the above and other objects in view 30 as the nature of the invention is better understood from the accompanying specifications and drawing, same comprises the novel combination and arrangement of parts hereinafter described and claimed.

In the drawings wherein like reference 35 characters indicate corresponding parts throughout the several views;

Figure 1 is a side elevation of a gate equipped with my novel closing and lock- 40 ing mechanism,

Figure 2 is a top plan view thereof,

Figure 3 is an enlarged detail transverse cross-sectional view taken substantially upon the line 3—3 of Figure 1,

Figures 4 and 5 are detailed perspectives of the elements comprised in my novel lock- 45 ing mechanism.

Now having particular reference to the drawings, 5 indicates a gate of any prefer- 50 able design supported in position between a pair of conventional type fence posts 6. One side of said gate 5 carries a pair of spaced eye-bolts 7 that are positioned between and in alignment with eyed ends of other eye- 55 bolts 8 that are anchored within the adja-

cent post 6. Extending through said eye-bolts is a pivot rod 9 that provides a pivotal connection between said gate 5 and the adjacent post 6.

Surrounding this pivot rod 9 at its upper and lower ends are helical springs 10, which are wound in opposite directions. The opposite ends of the said springs engage the gate 5 and said post 6 respectively as shown whereby a swinging movement of the gate 60 5 in opposite directions will tend to wind one of the springs for properly returning the gate to its normally closed position it being of course understood that the other of said springs will be slightly unwound. 70

Upon the inner side of the opposite fence post 6 and adjacent its upper end there is formed a cross channel more clearly shown in Figure 3 within which is received a keeper 11 for a pair of swinging latch elements 75 12 and 13.

The said keeper 11 embodies an oblong plate 14 formed at its opposite ends with openings whereby the same may be secured to the fence post 6 thru the medium of wood screws 15. Upon the upper and lower edges of said plate 14 and being of a length lesser than the length of the plate are inwardly extending flanges 16 that are formed adjacent their opposite ends with openings for purposes presently to be set forth, these flanges being turned inwardly at 17 at their opposite ends. 80

Each of the latch elements 12 and 13 comprises a body portion 18 in the form of an oblong plate the upper and lower edges thereof being formed with inwardly extending flanges 19 that are beveled toward their inner ends, i. e., the outer edges of these plates are inclined as more clearly shown in 90 Figure 5. The inner edges of said flanges 19 terminate short of the inner end of the body portion 18, these flanges being formed with aligned openings 20. The distance between the flanges 19 of each of the latch-elements is lesser than the distance between the flanges 16 of the keeper plate 14, whereby said flanges may be positioned within the flanges 16 of the keeper element to be 95 pivotally secured therebetween as at 21 105 through the medium of a pivot pin extending through the aligned openings in the flanges 16 of the keeper as well as the openings 20 in the flanges 19 of the latch members. 100

These latch elements 12 and 13 are normally maintained in an outward swung position as per Figure 3 through the medium of an expansion spring 22 which is positioned as shown in said Figure 3.

The adjacent side of the gate 5 carries an upwardly extending spring rod 24 which rod is anchored at its lower end within the gate frame and extends upwardly and then inwardly through an opening within the upper corner of the gate and then passes outwardly through a slot in the top frame bar of the gate, this end of the rod being formed with a knob head 25 whereby the said rod may be moved inwardly.

In view of the above description it will at once be apparent that when the gate 5 is maintained in a closed position through the medium of the latch elements 12 and 13, the gate may be opened by moving the spring rod 24 inwardly out of position between the pair of latch elements. A swinging movement of the gate in either direction will have a tendency to wind one of the coil springs 10 and upon a releasing of the gate the unwinding of the spring will move the same to its normally closed position and the spring rod 24 contacting with the adjacent one of the latch plates 12 and 13 will force this particular latch plate to swing inwardly under the influence of the spring 22 and consequently strike the other of the latch plates for preventing a further swinging movement of the gate.

Even though I have herein set forth the most practical embodiment of the present

invention with which I am now familiar it is nevertheless to be understood that minor changes may be made therein without departing from the spirit and scope of the invention as claimed:—

Having thus described my invention what I claim as new and desire to secure by Letters Patent is:—

A gate latch comprising a plate adapted to be applied transversely across a support at a gate opening, said plate being provided at its opposite longitudinal edges with parallel flanges, these flanges having angularly disposed extremities bent inwardly over the body of the plate, latch members comprising plates having plain intermediate body portions provided at their longitudinally disposed edges with parallel wings, the wings being pivoted to the flanges of the first mentioned plate at points between the ends of the body portions of the second mentioned plates whereby the end portions of the second mentioned plates are disposed transversely across the edges of the extremities of the flanges of the first mentioned plates and the wings of the second mentioned plates are received between the flanges of the first mentioned plates and springs interposed between the intermediate portion of the first mentioned plate, and the free end portions of the second mentioned plate and housed within the flanges and wings.

In testimony whereof I affix my signature.

WILLIAM Houser.
